ANTENNA REEL

Frank A. King, deceased, late of Los Angeles, Calif., by A. W. Tedstrom, Parsons, Kans., Ernest Lynn King, Los Angeles, Calif., and William Scott King, Los Angeles, Calif., administrators; said administrators assignors to Mary L. King, Tujunga, Calif.

Substituted for abandoned application Serial No. 520,110, January 28, 1944. This application April 2, 1948, Serial No. 18,657

7 Claims. (Cl. 242—99)

1

This invention relates to reeling mechanism for crank operated reels of any type and more particularly antenna reels; this application being in substitution for applicant's prior application Ser. No. 520,110, filed Jan. 28, 1944, now abandoned, which was a continuation in part of an application Ser. No. 411,676, filed Sept. 20, 1941, resulting in Letters Patent No. 2,363,533, issued November 28, 1944.

The primary object of this invention is the provision of a cranking mechanism having improved means controlling through the crank and crank handle for releasing the spool and it is especially adapted for controlling radio antenna in aircraft, in that it affords the desired control of the unwinding and reeling-in of the antenna as to rate of unwinding and length of antenna, it being possible to set the reel to hold any desired extension of trailing antenna and to change the length as desired, both with the nicety of control as to length and antenna movement, whereby a more reliable tuning of the aircraft radios may be effected.

An important feature of this invention is the novel provision of means including a coil spring arranged to wind-up, as the weighted antenna cable is unwound or extended, to a suitable predetermined length corresponding to the frequency of radio transmission.

A further object of this invention is the provision of means including a spring for impeding the unwinding movement of the weighted antenna cable which latter means also functions to provide automatic stopping of the antenna at a predetermined length.

Another important feature of the invention is the novel construction of detention means associated with a collapsible or compressible handle on the crank, arranged to restrain the clutch in a disengaged position during automatic unreeling of the antenna line in combination with a new form of pre-set clutch mechanism which is located on the outer side of the crank in the most convenient position for readjustment when necessary.

Another purpose of this invention is to provide in reeling mechanism an improved dual means for operating and controlling a combined frictional clutch unit for drivingly connecting and disconnecting the crank and the spool, and for setting up and releasing frictional resistance to rotation of the spool.

Fig. 1 is a fragmentary sectional view of the invention as embodied in a radio antenna reel.

Fig. 2 is a fragmentary sectional view taken on

2

the line 2—2 of Fig. 1, certain parts being shown in elevation.

Fig. 3 is a fragmentary elevational view of the reel shown in Fig. 1, certain parts being broken away to show other parts.

Fig. 4 is a transverse sectional view taken on the line 4—4 of Fig. 3, certain parts being broken away to show other parts.

Referring to Figs. 1 to 4 inclusive of the drawings more specifically, wherein this invention is embodied in an antenna reel; it is seen that such a reel includes a spool A similar to a pulley having a peripheral winding groove B of arcuate cross section and a link antenna anchor 1. The spool is mounted for free rotation on a tubular stud shaft 2 and driven by the crank C, having a handle D. This stud shaft is rotatable on a post 3, machined from hexagon stock, thus providing a reduced end 4 which is entered in a corresponding aperture in the support 5 and secured therein by peening over as at 4', the latter being secured on a support E by means of screws 6.

The opposite or outer end of post 3 is reduced in diameter, thus forming a shouldered end which abuts a corresponding internal annular shoulder 7 provided in the tubular shaft 2, the outer end of this shaft is provided with an internally threaded bore 8 slightly larger in diameter than

the inner marginal edge of the shoulder 7 thus forming a second shoulder 9 which faces outwardly and abutting this shoulder is a fillister headed screw 10 having internal screw-threaded engagement with the outer end of post 3. The outer end of shaft 2 is formed with diametrically flattened surfaces 11 which are fitted in a correspondingly broached opening in the crank C as indicated by the dotted line 1 as shown in Fig. 3, and the crank is secured thereon by means of a hexagon headed screw 13 having a screw threaded engagement with said bore 8.

The spool B is fabricated from Bakelite or other suitable frictional material and the back central portion of spool B is formed with an annular recess 14 and a cup shaped cavity having an annular tapered side wall 15. An apertured disk-like cover plate 16 serves to complete an enclosure for a scroll spring 17 in said recess 14. The inner end of spring 17 is attached to the hexagon portion of post 3 by means of a pin 18 and the outer end is secured to the inner wall of the recess 14 by the anchor pin 19.

The torsional resistance of the scroll spring to the spool in operation is suitably less than that produced by the unwinding of the weighted

antenna line as to approach counterbalancing thereof, therefore the spring tends to assist in the winding in operation and the correct adjusting of the line.

The shaft 2 constitutes a clutch element 20 formed integral therewith or otherwise, comprising a radial flange terminating in an annular conformed peripheral surface 21 conforming to the tapered side wall 15. Thus in turn the element 20 is also provided with a similar conformed cavity, having an annular recess therein 22 and the flange 20 is provided with apertures 23 which intersect the outer wall of the recess 22, thus forming a series of suitable semicircular notches which serve as ratchet teeth 24. The hexagon portion of post 3 carries a pawl supporting arm 25 interposed between the spring 17 and the recess 22. A pivot pin 26 supports a spring 27 which presses pawl 28 arranged to coact with said ratchet teeth 24.

As seen in the drawings the spool B is drivingly engaged with the clutch element 20 and the hub 29 abuts an apertured plate 30 which latter are axially movable on the shaft, a slight clearance being provided between plate 30 and the inner side of the crank C to accommodate this movement.

Pre-setting means F is mounted on the outer end of crank C in a most convenient location and comprises a knob 31 fixed to one end of a screw shaft 32 extending through compression spring 33, plate 30 and screw threadedly engaged with crank C.

Crank handle actuating means G, as shown in Figs. 1, 3 and 4 consists of a hollow shank 34 formed integral with the crank C having a reduced outer end 35 which is rotatable in an oval shaped cross finger piece 36, secured thereon by means of a threadedly engaged nut 37. A slideable pin 38, extending through the hollow shank 34, carries a semi-oval shaped gripping handle D formed with an oval cup-shaped hollow 39 corresponding to the oval shaped finger piece 36 over which it is adapted to slide for telescopic action.

Hollow 39 includes an inner boss 40 fixed to the outer end of pin 38 by means of a fillister headed screw 41, having internal screw-threaded engagement therewith and the opposite end is fixed as at 42.

The hollow of handle D is provided with a cavity which intersects the counterbore 43 for screw head 41, beneath which head is positioned a washer made of spring material having a curved tongue keeper 44 which by means of the cavity pivotally supports a hook end 45 of a detension member having a hook 46 at its opposite end which is adapted to co-act with the nut 37, there being a cavity 36a in the finger piece 36 for this purpose.

As seen in Fig. 3 the hub 47 of crank C is formed with a skirt 48 which conforms with the contour of plate 30 except that it converges with a tapering channel 49 extending to the free end of the crank. This channel 49 includes inwardly facing apertured bosses 50—50 pivotally supporting, by means of pin 51, a lever 52 the outer end 53 of which co-acts with the pin 38 and in turn the inner shorter end 54 is fulcrumed to the plate 30 by means of keeper lug 55.

It will be noted that the hub 47 is provided with an offset 56 which forms an opening 57 through which the plate is assembled and the tapered end 58 thereof is supported by the curved

counterbalance end of the crank having a seat 59 for this purpose.

The tension of spring 33 is regulated by turning knob 31 and by this means a setting of the clutch may be had as desired to drivingly connect and disconnect the spool, inasmuch as the spring 33 when under tension will yieldingly force the spool into frictional engagement with the brake or drag element 20 for winding in the antenna line.

Assuming now that the finger piece 36 and the handle D is given a firm squeeze by the operator's hand or the handle, D is merely pressed inwardly, the rod 38 will move the lever 52 as indicated by the dotted line 60 and the keeper 55 will move outwardly under the urge of spring 33 to release the clutch. The hook 46, being under the urge of spring keeper 44, will then snap into place behind the nut 37 to retain the clutch mechanism disengaged as indicated by dotted line 61, so that a weighted antenna may be unwound as the spring 17 is wound up to its full capacity when rotated in the direction as indicated by the arrow 61', which later serves to automatically stop the antenna within ranges of its predetermined radio tuning frequencies.

A novel press button means for releasing said detention hook 46, includes offset slide bars 62 and 63 formed with oppositely facing wedges 64 and 65, either one of which is adapted to lift the hook when moved thereunder by means of buttons 66—66 positioned at the apex of each tapered end of handle D in suitable apertures and in the most convenient location. The bars are attached to the boss by means of suitable screws 67—67.

If it is desired to readjust the antenna cable after permitting it to automatically stop paying out, the operator need merely press a button 66 and one of the wedges operated thereby will slide under the detention hook 46, whereby to disengage the latter and permit the spring 33 to re-engage the clutch element 20 and its connected handle D with the spool B which then is rotated by swinging the crank C to adjust the antenna frequency to the desired position and it is maintained in this position through the medium of the ratchet 24 and the pawl 28 until further operations are to be made.

It is evident that various changes may be resorted to in the construction, form and arrangement of the several parts without departing from the spirit and scope of this invention, hence it is not intended to be limited to the particular embodiment herein shown and described.

What is claimed is:

1. In a reeling mechanism, a support, a stationary post thereon, a tubular shaft rotatable on said post, a clutch member fixed on said shaft for rotation therewith, a spool rotatable and axially movable on said shaft, a second clutch member carried by and rotating with said spool, a crank fixed to said shaft, spring pressure means carried by the crank arranged to apply pressure against said spool for urging said clutch members into operative engagement with one another, and means on the crank movable for controlling said spring pressure means for clutching and declutching said clutch members.

2. In a reeling mechanism, a support, a stationary post thereon, a tubular shaft rotatable on said post, a clutch member fixed on said shaft for rotation therewith, a spool rotatable and axially movable on said shaft, spring means for limiting the rotation of said spool, a second clutch member carried by and rotating with said

spool, a crank fixed to said shaft spring pressure means carried by the crank arranged to apply pressure against said spool for urging said clutch members into operative engagement with one another, and means on the crank movable for controlling said spring pressure means for clutching and declutching said clutch members.

3. In a reeling mechanism, a support, a stationary post thereon, a tubular shaft rotatable on said post, a clutch member fixed on said shaft for rotation therewith, a spool rotatable and axially movable on said shaft, a second clutch member carried by and rotating with said spool, a crank fixed to said shaft, a plate carried on the crank and axially movable relative to said shaft and arranged to abut said spool, spring pressure means carried on the crank for urging said plate against the spool, and means operable on the crank for controlling the pressure of said plate against said spool.

4. In a reeling mechanism, a support, a stationary post thereon, a tubular shaft rotatable on said post, a clutch member fixed on said shaft for rotation therewith, a spool rotatable and axially movable on said shaft, a second clutch member carried by and rotating with said spool a crank fixed to said shaft, an adjustable screw shaft mounted on the crank to one side of the connection of the crank with the shaft, a plate mounted for movement axially of said screw shaft and disposed to bear against said spool, a spring arranged on said screw shaft to urge said plate against and axially move the spool, means by which said screw shaft is adjustable for varying the pressure exerted by said spring, and means carried by the crank and movable between the spool and said plate for regulating the pressure of the plate against the spool.

5. In a reeling mechanism, a support, a stationary post thereon, a tubular shaft rotatable on said post, a clutch member fixed on said shaft for rotation therewith, a spool rotatable and axially movable on said shaft, a second clutch member carried by and rotating with said spool, a crank fixed to said shaft, an adjustable screw shaft mounted on the crank to one side of the connection of the crank with the shaft, a plate mounted for movement axially of said screw shaft and disposed to bear against said spool, a spring arranged on said screw shaft to urge said plate against and axially move the spool, means by which said screw shaft is adjustable for varying the pressure exerted by said spring, means carried by the crank and movable between the spool and said plate for regulating the pressure of the plate against the spool, including a lever pivoted on said crank for moving said plate, an axially movable handle on said crank, and

means connecting the handle and lever for rocking said lever.

6. In a reeling mechanism, a support, a stationary post thereon, a tubular shaft rotatable on said post, a clutch member fixed on said shaft for rotation therewith, a spool rotatable and axially movable on said shaft, a second clutch member carried by and rotating with said spool, a crank fixed to said shaft, an adjustable screw shaft mounted on the crank to one side of the connection of the crank with the shaft, a plate mounted for movement axially of said screw shaft and disposed to bear against said spool, a spring arranged on said screw shaft to urge said plate against and axially move the spool, means by which said screw shaft is adjustable for varying the pressure exerted by said spring, means carried by the crank and movable between the spool and said plate for regulating the pressure of the plate against the spool, including a lever pivoted on said crank for moving said plate, an axially movable handle on said crank, means forming an operative connection between said handle and said lever, and means releasably locking said handle when said handle is axially moved into a predetermined position.

7. In a reeling mechanism, a support, a stationary post thereon, a tubular shaft rotatable on said post, a clutch member fixed on said shaft for rotation therewith, a spool rotatable and axially movable on said shaft, a second clutch member carried by and rotating with said spool, a crank fixed to said shaft, an adjustable screw shaft mounted on the crank to one side of the connection of the crank with the shaft, a plate mounted for movement axially of said screw shaft and disposed to bear against said spool, a spring arranged on said screw shaft to urge said plate against and axially move the spool, means by which said screw shaft is adjustable for varying the pressure exerted by said spring, means carried by the crank and movable between the spool and said plate for regulating the pressure of the plate against the spool, including a lever pivoted on said crank for moving said plate, an axially movable handle on said crank, means forming an operative connection between said handle and said lever, means releasably locking said handle when said handle is axially moved into a predetermined position, and means movable on the handle for releasing said locking means.
